UNITED STATES PATENT OFFICE.

FRANK E. MODLIN, OF ST. JOSEPH, MISSOURI, ASSIGNOR OF ONE-SIXTEENTH TO J. A. WHITE, OF SIOUX CITY, IOWA.

FUEL-GAS GENERATOR FOR INTERNAL-COMBUSTION ENGINES.

Application filed June 1, 1922. Serial No. 565,259.

To all whom it may concern:

Be it known that I, FRANK E. MODLIN, citizen of the United States, residing at St. Joseph, in the county of Buchanan and 5 State of Missouri, have invented certain new and useful Improvements in Fuel-Gas Generators for Internal-Combustion Engines, of which the following is a specification.

10 This invention relates to an improved fuel gas generator for internal combustion engines and seeks, as one of its principal objects, to provide a device whereby low grade oil or kerosene may be economically 15 employed as a fuel in connection with engines of this type.

The invention has as a further object to provide a device wherein, as compared with any system injecting or admitting a wet 20 fuel vapor to the engine cylinder, increased efficiency will be obtained by heating and gasifying the fuel vapor and mixing the resultant fuel gas with air to form a cool fuel mixture before reaching the engine cylinder so that more perfect combustion will 25 take place, this result not only tending toward the development of greater energy from a given amount of fuel but also tending to minimize fouling of the engine while 30 by cooling the gas by the admixture of auxiliary air, pre-ignition troubles or overheating of the engine will be avoided.

The invention has as a further object to provide a device embodying a shell forming 35 a combined gasifying and mixing chamber and wherein exhaust gases from the engine will be employed for heating the shell.

Another object of the invention in this connection is to provide a device wherein 40 the shell will be of spherical form and wherein a spherically shaped jacket will be provided to surround the shell in concentric relation thereto whereby to effect an equal distribution of heat about the shell.

A still further object of the invention is 45 to provide a device wherein moisture will be supplied to the fuel mixture for not only increasing the combustibility of the mixture but also retarding the formation of carbon 50 in the engine cylinder.

And the invention has as a still further object to provide a device which will be characterized by structural simplicity, which may be easily taken apart and 55 cleaned, and which will be well adapted for

use in connection with internal combustion engines of various conventional makes.

Other and incidental objects will appear hereinafter.

In the drawings:

Figure 1 is a vertical sectional view showing my improved gas generator applied, and

Figure 2 is a vertical sectional view showing a slight modification of the invention.

Referring now more particularly to the drawings, I have, for convenience, shown my device in connection with a conventional engine cylinder 10 having the usual intake chamber 11 and exhaust chamber 12 from which extends a nipple 13. In carrying the invention into effect, I employ a spherically shaped jacket 14 provided at one side with a nipple 15 threaded over the nipple 13 of the chamber 12 for connecting the jacket thereto and rising from the jacket is an annular flange 16. Bolted or otherwise secured to said flange is a cover plate 17 closing the jacket and threaded through said flange at the side of the jacket opposite the nipple 15 is an exhaust pipe 18.

Mounted within the jacket is a spherically shaped shell 19 and threaded through the shell at its upper side is an outlet pipe 20 which is also threaded through the cover plate 17 axially thereof. Thus, by rotating the pipe upon the cover plate, the elevation of the shell may be adjusted and, as shown, the shell is supported in concentric relation to the jacket so that a heating chamber 21 of uniform width is thus defined about the shell. Connected with the upper end of the pipe 20 is an elbow 22 from which extends a pipe 23 engaging a tee coupling 24. Connected to said coupling at its upper end is an auxiliary air inlet pipe 25 in which is interposed an appropriate control valve 26 and leading from the lower end of said coupling is a pipe 27 threaded through the wall of the chamber 11. Threaded through the jacket 14 and shell 19 beneath the pipe 18, is a combined primary air and fuel inlet pipe 28 bracing the shell with respect to the jacket and extending horizontally into the shell. This pipe carries a lock nut 29 to coact with the wall of the shell and mounted upon said pipe at its inner end is an elbow 30 carrying a depending nozzle 31 located axially of the outlet pipe 20 and terminating near the bottom of the shell.

Fixed upon the pipe 28 at its outer end is 110

a tee coupling 32 to which is connected a primary air supply pipe 33 of a diameter to admit only a restricted supply of air and threaded into said coupling at its upper 5 side is a combined fuel and moisture conducting pipe 34 equipped at its upper end with a tee coupling 35. Leading into this coupling at one side thereof is a liquid fuel supply pipe 36 in which is interposed an appropriate shut-off valve 37, and threaded into said coupling at its upper end is a water supply pipe 38 in which is interposed an appropriate shut-off valve 39.

As will now be seen in view of the preceding description, exhaust gases from the engine cylinder 10 will flow from the chamber 12 into the jacket 14 whence the exhaust gases will be distributed within the heating chamber 21 to flow around the shell 19 and 10 over the outlet pipe 20 to exhaust through the pipe 18. Thus, the shell will be heated throughout its entire area to provide an internal gasifying chamber while the outlet pipe 20 will also be heated, and, in this 15 connection, it is to be observed that the uniformity of width of the heating chamber 21 as well as the spherical shape of the shell will tend toward uniform heating of the shell. Furthermore, it is to be noted that 20 by employing a spherically shaped shell in conjunction with a spherically shaped jacket, the heating chamber 21 is without angles or pockets such as would prematurely collect soot to cause clogging of the chamber and 25 consequent local overheating of the wall of the jacket and shell or imperfect distribution of heat about the shell. However, by displacing the pipe 28 and detaching the cover 17, the shell may be removed from the 30 jacket, when the device may be readily cleaned. Since the gasifying chamber of the shell is in open communication with the chamber 11, engine suction in the latter chamber will, when the valve 37 is opened, 35 serve to draw in liquid fuel and air into the gasifying chamber. Upon entering said chamber the liquid fuel will, as will now be understood, be heated and gasified to become mixed with the air drawn in along with the fuel to form a hot fuel gas too rich to be 40 ignited. As the fuel gas rises through the pipe 20, said gas will then be further heated so that a thorough gasification of all liquid particles in the mixture will be had 45 when, as the gas continues in its flow through the pipes 23 and 27 toward the engine cylinder, a proper amount of auxiliary fresh air, admitted through the valve 26, will be drawn in to become mixed with the gas and thereby form a resultant explosive fuel mixture. The fresh air so introduced into the hot fuel gas will, at the same time, act as a 50 cooling agent for said gas so that a clean, cool, and dry explosive fuel mixture free of any liquid particles will be formed to thus

insure a cool-running engine and a clean cylinder or cylinders free from carbon or other deposit while allowing of a higher compression in the cylinder or cylinders without any pre-ignition trouble before the charge is 50 ignited. The richness of the mixture may, of course, be determined by adjustment of the valve 26 to admit auxiliary air to the fuel gas in regulated quantities, and I have found by actual test that by producing a 55 pre-gasified, cooled fuel mixture the efficiency of an engine is greatly increased in contrast with an arrangement wherein more or less wet fuel vapors are aspirated directly into the engine cylinder or cylinders. By 60 opening the valve 39, water will be admitted to the gassifying chamber along with the primary air and liquid fuel. Upon entering the chamber the water so admitted will, of course, be vaporized, when the steam thus 65 generated will become commingled with the fuel gas. As is well known, the combustibility of the ultimate mixture will thus not only be increased but also, the presence of the moisture in the mixture will 70 tend to reduce the formation of carbon in the engine cylinder. It is to be noted that only a restricted quantity of air is taken into the gasifying chamber along with the liquid fuel, only sufficient air being admitted to 75 effect a thorough gasification of the fuel. Premature expansion of the fuel gas is thus avoided while, when the fresh air is admitted to the gas during its flow to the engine, the cooling influence of the fresh air will 80 serve to prevent undue expansion of the explosive mixture formed by the introduction of the fresh air so that the full efficiency of 85 the mixture will be realized within the engine cylinder or cylinders. At the same 90 time, no condensation takes place, it having been found by actual test that the fuel mixture formed permanently retains its gaseous state.

In Figure 2 of the drawings, I have shown 95 a slight modification of the invention, this modified structure also being shown in connection with a conventional engine cylinder 40 having an intake chamber 41 and exhaust chamber 42 from which extends a nipple 43. A jacket 44 is employed, as in the preferred construction, this jacket being provided with a cover plate 45 having an exhaust pipe 46 leading therefrom. Mounted within the jacket is a shell 47 corresponding to the shell 19 and supporting the shell is an outlet pipe 48 threaded through the cover plate 45. At its upper end, the pipe 48 carries a coupling 49 connected by a pipe 50, a coupling 51, and a pipe 52, with the intake chamber 41. Connected to the coupling 51 is an auxiliary air intake pipe 53 in which is interposed an appropriate valve 54, as in the preferred construction. Threaded through the coupling 49 at its 100

upper end to extend axially through the pipe 48 into the shell 47, is a combined primary air and liquid fuel pipe 55 which, in the present instance, forms a nozzle terminating near the bottom of the shell and connected to the upper end of said nozzle is a coupling 56 carrying a primary air inlet pipe 57. Connected to the coupling 56 is a liquid fuel supply pipe 58 in which is interposed an appropriate shut-off valve 59 and connected to the pipe 58 is a water supply pipe 60 in which is interposed an appropriate shut-off valve 61. As will be seen, this modified structure provides an arrangement wherein the nozzle 55 enters the gasifying chamber of the shell through the outlet pipe of the shell whereas, in the preferred construction, the inlet pipe 28 is employed so that the outlet pipe for the shell is unobstructed. However, since when the shell 19 of the preferred construction must be relatively small, it may be found inconvenient to attach the nozzle 31, I have provided the modified structure wherein such difficulty will not be experienced. In other respects, the modified structure is identical in function and operation with the preferred form of the invention and further description thereof is accordingly believed unnecessary.

Having thus described the invention, what is claimed as new is:

1. A fuel gas generator for internal combustion engines including a jacket for connection with the exhaust outlet of the engine, a cover plate upon the jacket, a shell within the jacket, an outlet pipe extending from the shell through said plate for connection with the engine intake and connecting the shell with the plate to be removably supported thereby within the jacket, and means extending into the shell for supplying liquid fuel and air within the shell.

2. A fuel gas generator for internal combustion engines including a jacket for connection with the exhaust outlet of the engine, a shell mounted within the jacket, an outlet pipe extending upwardly from the shell exteriorly of the jacket for connection with the engine intake, a combined liquid fuel and air inlet pipe leading through the jacket into the shell, and a nozzle depending from the latter pipe within the shell.

3. A fuel gas generator for internal combustion engines including a jacket for connection with the exhaust outlet of the engine, a shell mounted within the jacket and provided with an upstanding outlet pipe for connection with the engine intake, a combined liquid fuel and air inlet pipe extending horizontally through the jacket into the shell, and a nozzle depending from the latter pipe within the shell axially of the outlet pipe.

In testimony whereof I affix my signature.

FRANK E. MODLIN. [L. S.]
